LINE-CASTING MACHINE.

1,156,040.

Specification of Letters Patent.

Patented Oct. 5, 1915.

Application filed February 12, 1915. Serial No. 7,816.

To all whom it may concern:

Be it known that we, (1) SAMUEL E. SPERRY and (2) WILLIAM H. ORPEN, Jr., citizens of the United States, residing at (1) Woodhaven and (2) Brooklyn, in the county of (1) Queens and (2) Kings, and State of New York, have invented new and useful Improvements in Line-Casting Machines, of which the following is a specification.

The present invention relates to improvements in line casting machines of the linotype class and more especially to those adapted to contain a plurality of matrix magazines, any one of which may be brought into use as desired, and the primary object is to provide simplified and relatively inexpensive means for shifting the magazines to bring the desired one into position to deliver matrices under control of the keyboard and to receive matrices returned thereto by the distributor, the present invention being an improvement upon that shown and described in the application of Thomas S. Homans, Serial No. 833,738, filed April 22, 1914.

In the accompanying drawing: Figure 1 is a side elevation of the upper portion of a machine of the linotype class and embodying magazine lifting means constructed in accordance with the present invention, and Fig. 2 is a diagrammatic view showing the parts shifted into a different position.

Similar parts are designated by the same reference characters in both views.

The invention is capable of use in connection generally with line casting machines of the type wherein matrices are stored in inclined magazines and are delivered therefrom under the control of the keyboard.

In the accompanying drawing, the invention is shown applied to a machine of the linotype class but it will be understood the invention is not restricted to the precise construction shown as equivalent constructions within the scope of the claims to be included.

In the present instance, 1 designates the upper portion of the main frame of the machine and 2 designates the bracket which supports the distributor, the main frame and distributor bracket being of the well known construction and the distributor is shown conventionally as of the type commonly used and comprising the combination rail 3 along which the matrices are fed by the screws 4

and a magazine entrance 5 which is located 55 below the combination rail and receives the matrices as they drop from the rail and conducts them into the respective channels at the upper end of the magazine. The magazine entrance is shown pivoted to the distributor bracket 2 at 6 whereby the magazine entrance may be swung to and from operative position between the distributor and the upper end of the magazine.

In the present instance, the machine is 65 adapted to contain two matrix magazines 7 and 8, these magazines being shown in inclined superposed relation and mounted on upper and lower magazine frames 9 and 10 respectively. Escapements 11 and 12 are 70 provided at the lower or delivery ends of the magazines to control the delivery of the matrices therefrom, this being effected under the control of the keyboard, the construction and mode of operation of which are well 75 known in the art, it being sufficient to show in the present instance, the vertically movable reeds 13 which are mounted in the main frame and are adapted to coöperate with the escapements of either magazine according to 80 which magazine is in operative position.

The present invention provides simple and improved means for shifting the magazines whereby any one of them may be brought into operative position to deliver matrices 85 as desired. In the construction shown, a shaft 14 is mounted in the main frame 1 and has an operating handle or lever 15 attached thereto. A pair of cranks or arms 16 are also connected to the shaft 14 and the 90 cranks are pivotally connected to the forward or lower end of the lower magazine frame 10 at 17. The lower magazine frame 10 is also formed at points adjacent to the pivots 17 with forks 18 and the main frame 1 is provided with a pair of fixed pins 19. Fig. 1 shows the parts in such relative position that the lower magazine is in condition to deliver matrices under control of the keyboard, escapements 12 of this magazine being in coöperative relation with the reeds 13 and the magazine is supported in proper position by the forks 18, which, at this time, rest upon the shaft 14 at opposite sides of the machine. When it is desired to bring 105 the upper magazine into position, to deliver matrices, the handle or lever 15 is rotated a half turn, the cranks or arms 16 then op-

erating first to lift the two magazines 7 and 8 bodily in a vertical direction, thus carrying the escapements 12 of the lower magazine clear of the reeds 13, farther rotation 5 of the handle or lever 15 carries the magazines bodily in a rearward direction, thus removing the escapements 12 of the lower magazine from above the reeds 13, and the final movements of the handle or lever 15 10 lowers the forward ends of the magazines, thereby bringing the escapements 11 of the upper magazine down into coöperative relation with the escapement actuating reeds 13. When the magazines reach the latter position, they are supported in such position by the forks 18 which then rest on the relatively fixed pins 19 of the frame. A half revolution of the handle or lever 15 is sufficient to shift the magazines from the position shown 15 in Fig. 1 wherein the lower magazine is in operative position, into the position shown in Fig. 2 where the upper magazine is in operative position and vice versa.

The upper or rear ends of the magazines 20 may be supported and guided in different ways. In the present instance, a shaft 20 is mounted in the distributor bracket 2 and has a pair of arms or links 21 thereon for the opposite sides of the machine, each of these 25 arms or links being pivotally connected to the magazines at 22. The arms or links 21 occupy such an angle on the shaft 20 that they will permit the magazines to move upwardly and rearwardly in order to bring 30 either of the escapements 11 or 12 into operative position and also to cause the upper ends of the magazines to shift a distance equal to the spacing of the magazines in order that the upper ends of the magazines 35 will be alined with or positioned properly to receive matrices from the magazine entrance 5. Any suitable means may be provided to swing the magazine entrance 5 clear of the rear ends of the magazines while the 40 latter are being shifted to bring the desired one into operative position, the entrance being swung to and from operative position about the pivot 6. If desired, this may be accomplished by hand, or, mechanical 45 means, such as that shown and described in the above-mentioned application, may be used.

According to the present invention, the lower ends of the magazines while being 50 shifted to bring the desired one into operative position move in a semi-circular path to clear the reeds of escapement actuating rods, and the upper ends of the magazines move in an arc of less angle, both ends of 55 the magazines being thus guided and supported without requiring linkage or other

mechanical connection between the guiding and supporting means.

Having described our invention, we claim:—

1. In a machine of the linotype class, in combination with a plurality of matrix magazines having controlling escapements, a movable frame supporting the magazines, escapement actuating means, means for 70 moving the lower ends of the magazines in a circular arc to bring the escapements of the different magazines into coöperative relation with said actuating means and means for moving the upper ends of the magazine 75 in a circular arc of relatively smaller angle.

2. In a machine of the linotype class, in combination with a plurality of inclined matrix magazines, a movable carrying frame for said magazines, means for moving the 80 lower end of the carrying frame in a circular arc, and means for moving the upper end of said frame through a circular arc of relatively smaller angle, the two means being connected solely by said carrying frame.

3. In a machine of the linotype class, in combination with a plurality of matrix magazines having controlling escapements, a movable frame supporting the magazines, escapement actuating means, cranks operatively connected to said frame for moving 90 the lower ends of the magazines in a circular arc to carry the escapements of the different magazines to and from coöperative relation with said actuating means, and links connected to said frame and operative to guide the upper ends of the magazines in a circular arc of relatively less angle.

4. In a machine of the linotype class, the combination with a plurality of matrix 100 magazines carrying controlling escapements, a movable frame supporting the magazines, actuating means for the escapements, means connected to said frame and operative to move the matrix delivery ends of the magazines in a circular arc to carry the escapements of the different magazines to and from coöperative relation with said actuating means, means actuated solely by said frame for guiding the upper matrix-receiving 105 ends of the magazines in an arc-shaped path, and a stop on the frame for supporting the different magazines in operative position.

In testimony whereof we have hereunto 115 set our hands in presence of two subscribing witnesses.
